UNITED STATES PATENT OFFICE.

FREDERICK H. BEACH, OF BATAVIA, ILLINOIS.

SHUTTLE.

1,199,335.

Specification of Letters Patent. Patented Sept. 26, 1916.

Application filed August 28, 1911. Serial No. 646,351.

To all whom it may concern:

Be it known that I, FREDERICK H. BEACH, a citizen of the United States, residing at Batavia, in the county of Kane and State of Illinois, have invented new and useful Improvements in Shuttles, of which the following is a specification, reference being had to the accompanying drawings, forming a part thereof.

10 The purpose of this invention is to provide a loom shuttle of greater capacity and durability than those now in use and also fitted with improved devices for holding the bobbin and for threading.

15 It consists of the features and elements described and shown in the drawings as indicated in the claims.

In the drawings:—Figure 1 is a top plan view of a shuttle embodying this invention. Fig. 2 is a medial section of the rear portion of the shuttle taken as indicated at the line 2—2, on Fig. 1. Fig. 3 is a transverse section taken as indicated at the line 3—3, on Fig. 2. Fig. 4 is a side elevation of the 25 shuttle illustrated in Fig. 1. Fig. 5 is a detail perspective view of the bobbin holder. Fig. 6 is a section at the line 7—7 on Fig. 1. Fig. 7 is a section of the line 8—8 on Fig. 2. Fig. 8 is a top plan view of the shuttle 35 slightly modified in construction. Fig. 9 is a section at the line 10—10 on Fig. 8.

The shuttle illustrated in the drawings comprises a body which may be made of only two pieces, as shown in Figs. 9 and 10, 40 but which may also be made as shown in the remaining figures, consisting of two relatively thin full length slabs, 1, and 2, and intermediate short blocks, 3 and 4, at the ends. Each of the side slabs, 1 and 2, is 45 suitably hollowed out on the surface which is to form the inner side of the completed shuttle. It will be noticed also that the shuttle is left open at the bottom, as seen at 7 in the drawings, for the entire distance between the interposed end blocks, 3 and 4, the width of the rift being substantially the thickness of said end blocks.

For proper operation in the loom, it is necessary that the bobbin should be centrally located in the shuttle cavity and that its axis should be quite accurately in line with the guide about which the yarn runs to the eye, so that the thread may at all times draw alike from all sides of the bobbin 55 as it unwinds. Whenever, by reason of any deficiency in the bobbin-holding means, the

bobbin leans to one side or the other, the yarn in running off the end of the bobbin is liable to be broken by the extra strain experienced in pulling it off at the side which is most out of line with the guide. Also, in the more common form of shuttles, the bobbin holder is of such construction as to occupy very considerable space in the solid end portion of the shuttle, thereby limiting the length of the bobbin cavity in the shuttle. For overcoming both of these defects, the shuttle shown in the drawings is adapted to receive a bobbin of ordinary construction,—consisting of a stem, 8, and a head or flange, 8^a, having a peripheral groove, 8^b, for holding the bobbin in the shuttle,—by means of the following construction: The bobbin-holder consists of a U-shaped seat or stirrup, 10, adapted to engage the flange, 8^a, of a bobbin at the groove, 8^b. This stirrup or holder is hung in the shuttle body by a pair of lugs, 12, lodged in the upper face thereof and secured by screws, 13.

In the more familiar forms of shuttle, 80 the bobbin is axially apertured and carried on a spindle mounted within the recess of the shuttle, while some form of catch is provided to engage a small portion of the peripheral groove, 8^b, for retaining the bobbin upon the spindle. Experience has shown, however, that there is considerable danger of the operator failing to fully insert the bobbin into proper engagement, and also of the flange, 8^a, splitting off back of 85 the groove, 8^b, at the point where it is engaged by such a catch, with the result that the bobbin is permitted to work off the spindle and often to fly out of the shuttle, becoming entangled in the warp and breaking the filling thread so as to cause damage and delay. The present form of holder, 90 consisting of the stirrup, 10, by engaging the groove, 8^b, throughout something more than half its circumference, so distributes 95 the strain that all danger of such splitting off the flange, 8^a, is obviated. The strength of the bobbin flange is further reinforced by the presence of a friction plate, 14, which is adapted to seat against the flat end of 100 the flange under the influence of pressure applied preferably near the center of the plate, thus tending to make the pressure uniform around that part of the groove, 8^b, which is in engagement with the holder, 10, 110 and further serving to keep the bobbin properly aligned with the shuttle; and this

is further assisted and the bobbin is accurately centered, by providing a slightly tapered centering stud, 14^a, on the plate, 14, which engages the axial aperture of the bobbin.

To prevent the bobbin from becoming disengaged from the holder, 10, and escaping from the shuttle during the operation of the loom, there is provided a guard, 15, consisting of the guard plate, 15^a, and a pair of bracket arms, 15^b, extending at right angles thereto into a recess, 1^b, in the rear end of the shuttle where they are pivotally secured upon the pin, 15^c. This adapts the guard to be raised upward to the dotted-line position illustrated in Fig. 2, so as to remove the guard plate, 15^a, from its locking position directly over the flange of the bobbin, and permit the removal of the latter from the fastener, 10, for re-filling of the bobbin, or any other purpose. The pivot pin, 15^c, is carried at one end of a spring, 16, secured in the end of the recess, 1^b, by a screw, 16^a, and designed to institute a thrust longitudinally of the shuttle. This thrust is communicated to the friction plate, 14, through a link, 17, pivotally connected to the arms, 15^b, by a pin, 15^d, and similarly yoked to the plate, 14, upon a pin, 14^a, carried in the lugs, 14^b, extending rearwardly from the back of the plate, 14. As the guard, 15, is swung down to locking position, the link, 17, assumes a position just below the line connecting the pins, 15^c and 14^a, and thus becomes an eccentric lock by virtue of the thrust of the spring, 16, for holding the guard, 15, in this position. Thus by the above described coördination of parts, there is produced a shuttle in which the bobbin is secured firmly and safely, though with the possibility of ready removal, and the safety of operation of the shuttle is considerably increased over that attending the use of the present familiar forms. Also this construction permits continued use of bobbins which may have had a portion of the flange broken, thus tending very materially to increase the length of time that they may be used before being discarded. It will be observed that in this construction the bobbin is positioned axially within the bobbin cavity of the shuttle by the seating on the friction plate, 14, which is held accurately in position by the thrust of the link, 17, on its flat cut end or bottom which is on the end of the grain of the wood of which the bobbin is made, and thereby adapted to endure maximum wear and pressure without being worn or forced out of true plane. Also the devices for holding the bobbin are very much less in weight than those commonly employed, in which there is a long spindle carried by them on which the bobbin is mounted. The lightness of the bobbin-holding devices obviates

the necessity of counterweighting the opposite end of the shuttle with lead, as is frequently necessary in the shuttles of common construction. The balancing of the shuttle is of great importance, because, if not balanced, the heavier end being always that in which the bobbin is secured, tends to tip down when the shuttle is in motion, and is thereby caused to strike the edge of the shuttle box, causing the shuttle often to be badly roughened or broken at that end. The bobbin-holder herein shown and described is but very little heavier than the amount of material removed from the shuttle body in order to receive said bobbin-holder, and the shuttle is therefore left well balanced.

I claim:—

1. In a loom shuttle, a bobbin holder comprising an upwardly open U-shaped plate adapted to engage a peripherally grooved bobbin base, a flat plate parallel to said U-shaped plate situated between the end of the shuttle and said U-shaped plate and mounted for movement toward and from the latter, and means adapted for exerting a yielding pressure to hold said flat plate against the bobbin base.

2. In a loom shuttle, a bobbin holder comprising an upwardly open U-shaped plate adapted to engage a peripherally grooved bobbin base, the edges of said plate extending upward and parallel to each other from either end of its curved U-shaped outline for engagement with said peripheral groove of the bobbin above the horizontal diameter of the latter, and means adapted to exert a pressure against the bobbin base for seating the side wall of said groove against the U-shaped plate.

3. In a loom shuttle, a bobbin holder comprising an upwardly open U-shaped plate adapted to engage a circular and peripherally grooved bobbin base, the edges of said plate extending upward and parallel to each other from either end of its curved U-shaped outline for engagement with the said peripheral groove of the bobbin above the axis of the latter, a flat plate positioned for contact with the end of the bobbin base, and means for thrusting said flat plate against said base, comprising a link pivoted to the plate below the bobbin axis.

4. In a loom shuttle having its body recessed to accommodate a bobbin holder mounted in said recess, adapted to engage a peripheral groove in the base of the bobbin, a friction plate mounted for movement toward and from the end of the bobbin which is engaged in the holder, a guard pivoted on the shuttle for swinging against the bobbin at the side of the latter not engaged by the holder, and a link connecting the swinging guard and the friction plate for simultaneous operation of said elements.

5. In a loom shuttle having its body re-

130

- cessed to accommodate a bobbin holder mounted in said recess, adapted to engage a peripheral groove in the base of the bobbin, a friction plate mounted for movement 5 toward and from the end of the bobbin which is engaged in the holder, a guard pivoted on the shuttle for swinging against the bobbin at the side of the latter not engaged by the holder, a link connecting the 10 swinging guard and the friction plate for simultaneous operation of said elements, and a spring positioned to react between the shuttle body and the friction plate for holding the latter against the end of the bobbin.
- 15 6. In a loom shuttle having its body recessed to accommodate a bobbin holder mounted in said recess, adapted to engage a peripheral groove in the base of the bobbin, a friction plate mounted for movement 20 toward and from the end of the bobbin which is engaged in the holder, a guard pivoted on the shuttle for swinging against the bobbin at the side of the latter not engaged by the holder, a link having its ends 25 pivotally connected to the friction plate and the swinging guard, respectively, the guard pivot of the said link being positioned to lie off the line connecting the plate pivot of the link and the pivot mounting of the
- guard when the latter is in locking position 30 against the bobbin, and a spring positioned to institute a thrust along the link when the guard is in said locking position.
7. In a loom shuttle having its body recessed to accommodate a bobbin, a holder 35 mounted in said recess adapted to engage a peripheral groove in the bobbin base, a friction plate mounted in the shuttle for movement toward and from the end of the bobbin, a spring mounted in the shuttle to act 40 in the direction of movement of said friction plate, a guard pivoted upon the yielding portion of the spring for swinging against the bobbin at the side of the latter not engaged by the holder, and a link pivotally 45 connecting the guard and the friction plate, the guard pivot of said link being positioned to lie off the line connecting the plate pivot of the link and the pivotal mounting of the guard when the latter is in locking position 50 against the bobbin.

In testimony whereof, I have hereunto set my hand, at Batavia, Illinois, this 24th day of August, 1911.
